(57) CLAIM

The ornamental design for a handbag, as shown and described.

DESCRIPTION

FIG. 1 is a perspective view of a handbag showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines crossing claimed surfaces on the exterior of the bag depict stitching and form no part of the claim. The interior of the bag shown in broken lines forms no part of the claim.

1 Claim, 7 Drawing Sheets
